UNITED STATES PATENT OFFICE.

EZEKIEL J. WILSON, OF EAST GREENBUSH, AND EDWIN A. REES, OF ALBANY, NEW YORK, ASSIGNORS TO F. C. HUYCK & SONS, OF RENSSELAER, NEW YORK, A CORPORATION OF NEW YORK.

METHOD OF REGULATING THE OPERATION OF PAPER-MAKING MACHINES.

Application filed April 28, 1925. Serial No. 26,391

To all whom it may concern:

Be it known that we, EZEKIEL J. WILSON and EDWIN A. REES, citizens of the United States, residing at East Greenbush, in the county of Rensselaer, and Albany, in the county of Albany, respectively, and State of New York, have invented certain new and useful Improvements in Methods of Regulating the Operation of Paper-Making Machines; and we do hereby declare the following to be a full, clear, and exact description of the invention, such as will enable those skilled in the art to which it appertains to make and use the same.

15 The invention relates to paper manufacture and more particularly to a method by which excessive stresses on the felts of paper making machines may be determined and eliminated, and the efficiency of the machine 20 as well as the efficiency and life of such felts increased.

While the invention is of more general application, it may be utilized with particular advantage in connection with cylinder or 25 paper board machines, wherein the stress put upon the felts is usually heavy and varies widely at different points in its travel due to the number of cylinders and press rolls driven thereby.

30 In cylinder or paper board machines, the felts not only cooperate with the cylinder molds and couch rolls and with the press rolls in forming and partially drying the sheet of paper stock, but also serve to transmit motion from the power driven press 35 rolls to the cylinders and couch rolls and to the other press rolls. The pull or stress on the felt therefore, increases as the felt passes between and drives successive cylinders and couch rolls and successive pairs of press 40 rolls, is or should be the maximum at the point where the felt leaves the last pair of press rolls driven thereby, and is released as the felt emerges from between the power 45 driven press rolls and returns to the first cylinder and couch roll. The pull or stress thereon causes a strain or stretch of the felt and upon the release of the stress, the elasticity of the felt causes it to return to its 50 normal length. There is therefore a repeated stretching and contracting of the felt during operation of the machine which tends to gradually break down the felted bonds and to cause the felt to stretch out

more and more each day, thus destroying 55 its efficiency and eventually requiring its replacement by a new felt.

It becomes important, therefore, that the stress and strains to which the felts are subjected at different points in their travel be 60 determined and that the machine and its different mechanisms be regulated or adjusted to properly distribute the stresses on the felts and thus eliminate any excessive stress indicated and to reduce as far as possible 65 the maximum stress tending to impair the efficiency and shorten the life of the felts. The present invention provides a method for securing this result, and also a method which enables a given machine to be equipped with 70 felts which are best suited for long efficient operation under the proper conditions of use in such machine.

In accordance with the present invention, the strain, stretch or elongation of the felt at 75 different points in its travel is determined by measuring the length of the entire felt or of a predetermined portion thereof passing these points. This may be done conveniently by any suitable form of measuring wheel 80 placed in engagement with the felt to indicate the length passing the point of engagement. By thus measuring the stretch of the felt at different points, the point or points of greatest stretch and therefore of greatest 85 stress or pull may be determined, as well as the comparative stress or pull between successive points in the travel of the felt. The occurrence of an excessive or undue stretch indicating an excessive stress or pull at any 90 point or points in the travel of the felt may thus be detected and steps taken to remedy the abnormal or inefficient condition indicated. By measuring the stretch of the felt after each station at which the felt does 95 mechanically work, ineffective or improper adjustment or operation of devices at any station tending to unduly or improperly resist the travel of the felt may be detected and the devices adjusted or regulated to 100 properly distribute the load on the felt and to reduce it to a minimum. This not only contributes to the efficiency and longevity of the felt, but also increases the efficiency of 105 the machine and permissible speed of operation.

The determination of the maximum stretch of the felt under efficient operating

conditions also permits the maximum stress to be calculated from obtainable data as to the elongation of its yarns under known stresses. The use of felts which have not the 5 tensile stretch or are otherwise ill adapted to withstand the indicated stresses or the repeated stretching and contraction indicated may thus be avoided or discontinued and felts selected and used which are best 10 suited for use under the indicated conditions.

The invention will be further explained in connection with its application to a paper board machine of the type illustrated, 15 grammatically in the drawings in which Figure 1 is a diagram showing the paths of travel of the felts through the machine, and Figure 2 is a plan view of a suitable form of instrument for measuring the length of 20 the felt at the desired points.

The machine illustrated in Figure 1 comprises a lower felt 4 driven from the lower roll 6 of the last pair of press rolls and passing over a series of idler and tension rolls 25 8 and 10 and over a plurality of cylinder molds 12, each of which is arranged to rotate in a vat 14 and each of which cooperates with a couch roll 16 pressing against the upper side of the felt. As is usual in this 30 type of machine, the vats contain paper stock which is carried by the successive molds onto the under side of the felt. From the last cylinder and couch roll, the felt passes over a roll 18 and between a pair of 35 guide rolls 20 where it meets with the upper felt 22 which is driven from the upper roll 24 of the last pair of press rolls and passes over a series of idler and tension rolls, as shown in Fig. 1. The two felts between 40 which the paper stock is carried pass together between the series of pairs of press rolls 26 in the usual manner and thence around the press rolls 6 and 24, the sheet of paper stock passing 45 out from between the felts and to the drier which may be of any usual form. The press rolls 6 and 24 of the last press are driven by any suitable gearing connection from a driving pulley 28. The last press 50 rolls are usually the only ones of the machine which are driven from an external source, the felts themselves constituting the driving means for the cylinder molds and couch rolls and for the press rolls.

55 Considering, for example, the lower felt 4, it will be seen that in its traverse through the various parts of the machine, it is subjected to a progressively increasing tension or pull which is a minimum between the 60 driving roll 6 and the first cylinder mold and which increases in value for each cylinder and couch roll and for each pair of presser rolls through which the felt passes and which reaches a maximum at a point between the last pair of driven press rolls 65 26

and the driving press rolls 6, 24. This increasing tension or stress gives rise to a correspondingly increasing stretch, strain or elongation in the felt. The upper felt 22 undergoes a similar variation in tension and stretch.

The measurement of the length of felt which passes a selected point may be conveniently made by means of a measuring device of the type shown in Fig. 2 comprising a measuring wheel 30 and indicating mechanism 32 mounted on a suitable handle 34. To measure the length of felt passing a selected point and thus determine the extent to which the felt is stretched at this 75 point as compared to its normal length, the wheel 30 is placed upon the felt at the point at which the measurement is to be made and is maintained in contact therewith while the felt is making one complete revolution or 80 while a portion between two fixed points on the felt travels past the wheel. While a selected portion of the felt only may be measured, it will usually be found to be more 85 convenient to measure the length of the entire felt travelling past the point or points at which measurement is made.

As already indicated, the length of the travelling felt may be measured after it has 90 passed each cylinder and couch roll and after it has passed each pair of press rolls, and thus the stretch of the felt due to its operation of each of the devices may be determined as well as the maximum stretch to 95 which it is subjected and the extent to which it stretches and contracts during each revolution or complete travel through the machine. Improper adjustment or regulation of any of the mold cylinders and couch rolls 100 of any of the pairs of press rolls may be thus detected and the proper adjustment or regulation made to secure the proper and efficient 105 operation of the various mechanisms and the proper distribution of the stresses on the felt. The maximum stress to which the felt 110 should be subjected under proper working conditions may also be determined as already indicated and the use of felts which are ill adapted for withstanding such stresses may 115 be avoided. The continued operation of the machine under conditions which put an abnormal and unnecessary pull or stress upon the felt and which could not otherwise be detected, may also be avoided by measuring 120 the stretch of the felt at the point of maximum stress and comparing it with the stretch which former tests have demonstrated should occur under proper working conditions.

125 While the invention has been described in connection with and is particularly applicable to paper board machines, it is not to be considered as limited in its application to such machines but may be applied with advantage to the determination of the stresses 130

and strains in felts of other machines or mechanisms or in analogous travelling webs which are subject to varying tensions throughout their course of travel.

5 What is claimed is:

1. A method of regulating the operation of paper making machines provided with endless felts which drive one or more devices thereof, which consist in determining the stresses or strains in the travelling felt by measuring the length of a predetermined portion of the felt passing a selected point or points, and adjusting the machine to eliminate abnormal stresses or strains indicated.
- 10 2. A method of regulating the operation of paper making machines provided with endless felts which drive one or more devices thereof, which consists in measuring the length of a predetermined portion of the felt at successive points in its travel to determine the stretch of the felt at such points,

and regulating the devices driven by the felt to eliminate abnormal stretch indicated at any point.

25

3. A method of determining stresses or strains in the travelling felt of a paper making machine or analogous travelling web subjected to varying degrees of tension which consists in measuring at one or more points in its travel the length of a predetermined portion of the felt as compared with the length of such portion free of tension.

30

4. The method of determining the stress on the travelling felt of a paper making machine at a selected point in its travel which consists in measuring the length of a predetermined portion of the felt passing that point as compared with the normal length of said portion.
